US00D579561S

(12) **United States Design Patent**
Call et al.

(10) **Patent No.:** **US D579,561 S**
(45) **Date of Patent:** **** Oct. 28, 2008**

(54) **PORTION OF A SYRINGE**

(75) Inventors: **Evan W. Call**, Bountiful, UT (US);
Edwin Lewis Pangman, West Jordan,
UT (US)

(73) Assignee: **Physician Industries, Inc.**, West Valley
City, UT (US)

(**) Term: **14 Years**

(21) Appl. No.: **29/269,668**

(22) Filed: **Dec. 6, 2006**

Related U.S. Application Data

(63) Continuation of application No. 10/831,769, filed on
Apr. 23, 2004, now Pat. No. 7,291,131, which is a
continuation-in-part of application No. 10/769,634,
filed on Jan. 30, 2004.

Primary Examiner—Louis S Zarfas*Assistant Examiner*—Eric L Goodman*(74) Attorney, Agent, or Firm*—TraskBritt, P.C.(57) **CLAIM**

The ornamental design for a portion of a syringe, as shown and described.

DESCRIPTION

FIG. 1 is a perspective view of a portion of a syringe showing our new design;

FIG. 2 is a side of the portion of a syringe shown in FIG. 1; and,

FIG. 3 is a bottom view of the portion of a syringe shown in FIG. 1.

The uneven broken lines represent the remaining portion of the syringe. The uneven broken line representations in FIGS. 1–3 are for illustrative purposes only and form no part of the claimed design.

1 Claim, 3 Drawing Sheets
